TOY ANIMAL FIGURE

Laura Slobe, New York, N. Y.

Application April 9, 1956, Serial No. 40,963

Term of patent 7 years

(Cl. D34—2)

Figure 1 is a front elevational view of a toy animal figure showing my new design.

Figure 2 is a back elevational view of the toy animal figure.

Figure 3 is a top view of the toy animal figure.

Figure 4 is an elevational view of the right side of the toy animal figure.

Figure 5 is an elevational view of the left side of the toy animal figure.

I claim:

The ornamental design for a toy animal figure, as shown.
